WAVE TRANSMISSION

Harry Nyquist, Millburn, N. J., assignor to Bell Telephone Laboratories, Incorporated, New York, N. Y., a corporation of New York

Application June 5, 1940, Serial No. 338,889

13 Claims. (Cl. 178—44)

This invention relates to electric signal transmission systems and more particularly to the measurement and reduction of deleterious effects due to repeated partial reflection of the signals at spaced points in the transmission path.

It is well known that in long wire line signal transmission systems the line is usually not electrically smooth; that is, electrical irregularities or impedance discontinuities appear at many points along the line. These discontinuities may appear at signal repeater stations in the line or at any other point where electrical apparatus is connected to the line conductors, and they may appear to a lesser degree at splicing points and even within splicing lengths. At each such discontinuity some of the signal power is reflected and proceeds back towards the signal source until it is blocked, as by the output circuit of a unidirectional signal repeater. The reflected power may on its way strike another impedance discontinuity whereupon some of the power is again reflected and proceeds in the direction of the original signal but delayed by the time consumed in twice traversing the distance between the two discontinuities. The signal component thus delayed eventually reaches the receiver at the far end of the line where it manifests itself as a distinct echo, if it be long enough delayed, or as distortion or as a "ghost" image if the signals are television signals. Reflection effects of the general kind illustrated in the foregoing description may all be designated as echo effects, more particularly as listener echo effects, whether the signals are of audio frequency or not. To mitigate them is a principal object of the present invention.

Heretofore efforts have been made to eliminate or electrically smooth out the impedance irregularities giving rise to echo effects, or echo suppressors have been employed in speech transmission systems, where appropriate, to disable the transmission circuit momentarily during pauses in the conversation so that the echo cannot be heard. The first of these remedies entails a search for the discontinuities and complicated and expensive compensating networks at each discontinuity; it is not suited for compensation of discontinuities that appear within a reel length or splicing length of shielded cable; and it would require sacrifice of certain advantages accompanying intentional mismatch of impedances at the input circuits of signal repeaters. The second remedy is of limited applicability and is quite inappropriate for television transmission systems. In systems of the latter kind

the problem of reduction or substantial elimination of echoes is an aggravated and increasingly important one because an echo need be delayed less than a millionth of a second behind the signal for it to require attention.

In accordance with the present invention many of the disadvantages of prior art methods and means for reducing echo effects are largely avoided, and certain impedance discontinuities that could not practically be reached and corrected heretofore are effectively compensated. The invention also permits impedance irregularities to remain in the system as, for example, where their presence may be desirable for other reasons or where their number makes individual correction quite impractical, and yet permits correction of the echoes to which they give rise. In general the invention provides for the generation of one or more synthetic echoes and for their introduction into the signaling system at such points and with such respective delay, amplitude, phase and frequency composition that the synthetic echoes and echoes arising in the signaling system effectively offset or neutralize each other. More particularly, in accordance with preferred embodiments of the invention, a portion of the wave power is diverted from the signaling system at a suitable point and transmitted through an auxiliary transmission line or other transducer of substantial electrical length, from which it is then returned to the signaling system, delayed just long enough by its passage through the auxiliary transducer for it to meet an echo following the signal. The amplitude and frequency composition of the wave power thus returned to the system is or can be adjusted accurately to match the same parameters of the echo to be neutralized and its phase can readily be so adjusted that the original echo and the synthetic echo are in phase opposition whereby they neutralize or tend to neutralize each other. Any number of echoes can be neutralized in the same manner by withdrawing wave power from the auxiliary transducer at various points along its length such that the delay encountered in transmission to those points coincides with or is otherwise critically related to the respective delays of the several echoes.

Various specific objects of the invention are attained in the preferred embodiment by such features as the following. First, the auxiliary transducer is made in the form of a transmission line whereby the delay of the synthetic echoes can be precisely and substantially continuously adjusted

for a wide range of frequencies and over a wide time delay range. Second, the auxiliary line is designed to have the same propagation characteristics as the signaling line, so that the synthetic echoes are modified by the auxiliary line characteristics in the same manner as the echoes in the signaling line. Third, frequency discriminatory transducers are associated with the auxiliary transducer to alter the frequency composition of the synthetic echoes in the same manner that the echoes in the line are altered by the frequency discriminatory characteristic of the impedance discontinuities causing them. Fourth, separate frequency discriminating transducers are associated with the auxiliary transducer so that the modification of frequency composition introduced may be adjusted to the several frequency characteristics of the principal echo-producing discontinuities. Fifth, the auxiliary line is designed to have a relatively low velocity of propagation whereby the necessary delay can be realized in a short length of line. Sixth, to obviate an impedance discontinuity at the junction of the auxiliary transducer and the signaling line, the junction is placed between stages of a signal repeater amplifier. Seventh, in a transmission line having a large number of signal repeaters spaced apart therein, the echoes generated in a plurality of repeater sections are all neutralized at one point along the line; and in accordance with a related feature, the spacing of the principal discontinuities is made the same in each repeater section so that the principal echoes coincide in time delay. Eighth, to reduce the required length of auxiliary line, the latter is connected between widely spaced points along the signaling line. These and other features, objects and advantages of the invention will appear more fully in the appended detailed description of several illustrative embodiments.

The practice of the invention as above described and more especially the adjustment of the length of the auxiliary transducer is simplified by use of a device for continuously representing the echo-producing characteristics of the transmission system so that the effect of adjustments of the neutralizing apparatus can be readily ascertained.

In accordance with a preferred embodiment of the latter phase of the present invention, periodic current pulses are transmitted through the signaling system where they give rise to like current-pulse echoes. The latter are separated at a neutralizing point from the pulses producing them and there caused to appear on the screen of a cathode ray tube, where also will appear the synthetic echoes introduced into the system. As the effective parameters of the echo neutralizing line are adjusted, there are corresponding changes evident on the screen of the cathode ray tube and it may be seen whether a given adjustment is in the proper sense to neutralize a given echo, and whether and to what extent the final adjustment is effective.

In the further exposition of the invention reference will be made to the accompanying drawings, in which:

Figs. 1 to 4 are diagrams illustrating schematically how echoes arise from impedance discontinuities in a typical transmission system;

Fig. 5 illustrates in idealized form one embodiment of the invention;

Fig. 6 shows an actual combination in accordance with the invention;

Fig. 7 shows a modified form of the invention

in which the required delay of the neutralizing echoes occurs partly in the signaling line;

Fig. 8 shows an embodiment with provision for differently modifying the frequency composition of different sets of synthetic echoes;

Fig. 9 features an auxiliary transducer that is in the form of an electrically long but physically short acoustic transmission line;

Fig. 10 shows schematically a preferred arrangement for obtaining a visual representation of the echo-producing characteristics of the signaling system; and

Fig. 11 illustrates a detail thereof.

Referring now more particularly to Fig. 1, there is represented schematically a portion of a signaling system comprising a line for the transmission of signals S and two successive signal repeaters 10 and 11 spaced apart in the line. Within the repeater section a few electrical irregularities or impedance discontinuities in the signaling circuit are represented at points 1 to 4 and at these points there is partial reflection of the signal power. It is assumed that at the output terminals O of the first repeater 10 there is a substantial discontinuity and that at the input terminals 5 of the second repeater 11 there is no discontinuity and no reflection of the signal power. On passing from one repeater to the next the signal S strikes the successive discontinuities 1 to 4 and at each of these points a portion of the signal power is reflected and proceeds toward the repeater 10. On reaching the large discontinuity 0 at the output terminal of repeater 10 the several reflected portions are again reflected and they now proceed toward repeater 11 in the same direction as the main body of the signals. While these reflections take place the signal continues to advance in the direction of normal propagation, and the several doubly reflected portions of the signal are accordingly relatively retarded or delayed.

Fig. 2 shows diagrammatically the relation between the signal and the several echoes produced in the manner described with reference to Fig. 1. The echo 1-0, produced by successive reflections at points 1 and 0, is delayed by the time consumed in twice traversing the distance between points 0 and 1; the delay of echo 2-0 is similarly measured by twice the separation of discontinuities 0 and 2; and so on. The last echo 4-0 has a delay comparable with twice the electrical length of the repeater section. Assuming that the velocity of propagation is substantially uniform throughout the repeater section, the respective delays of the several echoes may be represented in terms of distance, as indicated in Fig. 2.

If there is a substantial impedance discontinuity at the input terminal 5 of the repeater 11, also, as represented in Fig. 3, an additional set of echoes will appear. Thus the signal power reflected at the discontinuity 5 will return toward repeater 10 and on its way strike the several intermediate discontinuities 1 to 4. At each such point some of the wave power is again reflected and resumes propagation in the direction of the signal. Of the added set of echoes the one least delayed is that designated 5-4, and the one with greatest delay 5-0 is displaced behind the signal by twice the electrical length of the repeater section. In considering Figs. 1 to 4 it should be appreciated that the relative intensity of an echo is affected by line attenuation and that more particularly it tends to decrease as the distance between the pair of discontinuities giving rise to it increases. Its intensity depends also on the de-

gree of impedance mismatch at the significant discontinuities and its relative phase is determined by the sense in which the impedance changes at the discontinuities.

In a long transmission system comprising many repeater sections the effect described with reference to Figs. 1 to 4 will tend to arise in each section. Although the total number of echoes in the system will therefore tend to increase in proportion to the number of sections, it is important to note that none of the echoes ordinarily significant will be delayed by an amount more than that corresponding to twice the electrical length of the longest repeater section. Although there may be, therefore, a large number of echoes superposed in the same time interval, the problem of neutralization in accordance with the present invention is simplified at least to the extent that the maximum delay is not proportional to the length of the system.

In view of the considerations outlined hereinbefore, it may now be evident that in a system in accordance with applicant's invention it is desirable to observe several conditions in practice. First, the line should be as electrically smooth as possible near the ends of each repeater section or at least near that end where there is a substantial discontinuity at the repeater, for the relative intensity of the echoes arising in those portions of the line is least reduced by attenuation. It will contribute to the desired electrical smoothness where the line is a cable or otherwise prefabricated, if the various splicing lengths making up the line are arranged in the same order in which they are taken from the reel, and if the reel or cutting lengths in turn are arranged in the same order in which they were taken from the fabricating machine. The facing line impedances, then, at the junctions of splicing lengths and of cutting lengths will tend to be equal and the probability of a substantial impedance discontinuity is minimized. In view also of the special nature of applicant's invention it is desirable that the pairs of discontinuities giving rise to substantial echoes be equally spaced in successive repeater sections. Thus for specific example it is recommended that the electrical length of the cutting length adjacent a repeater be made precisely the same in all other repeater sections, and that the electrical lengths of successive repeater sections be precisely the same if the discontinuities represented at 0 and 5 in Fig. 3 are marked enough to contribute a significant echo. With the spacing of discontinuities as herein recommended the echoes produced in one repeater section will coincide in time delay with the respectively corresponding echoes produced in all other repeater sections, with the net result that the total number of significant echoes to be neutralized will be substantially reduced.

Fig. 5 illustrates a portion of a long wire line signal transmission system comprising a shielded-pair cable 12 and signal repeaters spaced apart therein, with provision in accordance with the invention for the mitigation of echo effects. In this example, as well as in the others to follow, it may be assumed for purposes of specific illustration that the signals transmitted through the system are television signals occupying the frequency range lying between 50 and 2500 kilocycles per second, that the velocity of signal propagation through the line is approximately 170,000 miles per second, and that the repeaters are spaced about five miles apart. It may be assumed further that at the output terminals of one of

the repeaters 11 there appears in addition to the signal a plurality of substantial echoes which it is desired to eliminate so that a signal free of echoes may be delivered to an immediately adjacent terminal station or to another section of line for transmission ultimately to a remote terminal station. It may be noted here that from a theoretical standpoint it is immaterial and not of controlling importance whether the synthetic or neutralizing echoes introduced in accordance with the invention be introduced at a point in the line following the discontinuities giving rise to echoes but for various reasons it is convenient and advantageous to do so. It should be borne in mind, however, that it is quite feasible to introduce the synthetic echoes at the point where the signals are first applied to the cable.

At the output terminals of repeater 11 in Fig. 5 a portion of the signal power is diverted to a signal amplifier 8 and caused to propagate corresponding signal waves through a transmission path 13. The latter may be a shielded circuit similar to cable 12 and its electrical length is at least as great as the space or distance delay of the most retarded echo to be neutralized. At its remote end the auxiliary line 13 is terminated in an impedance matching resistor 14 so that there is no wave reflection at the remote end. At various points along line 13 wave power is diverted through resistors 16 to a pair of bus-bars 15 from which they are applied through amplifier 7 to the line 12 at the output of repeater 11. The bus-bars 15 may be assumed to have substantially zero electrical length, a condition that can be realized in practice as will appear from examples presented hereinafter. The position of any given resistor 16 along the line 13 is so adjusted that the time required for the signal to travel from the output of repeater 11 to the given resistor coincides with the time delay of a given echo to be neutralized. The magnitude of the resistor is so adjusted that the intensity of the synthetic echo introduced into the line through amplifier 17 is equal to that of the given echo to be neutralized. The phase of a given synthetic echo can be readily changed 180 degrees by connecting its associated resistor 16 with one or the other of the bus-bars 15.

One may ordinarily dispense with the amplifiers 8 and 7 in Fig. 5 or adjust them to zero or subzero gain. If they are omitted separate provision should be made for adjusting the amount of signal power diverted from the line 12 and for avoiding or minimizing an impedance discontinuity at the point of connection of line 13 and bus-bars 15. Account should be taken too of the fact that in the absence of unilateral devices such as 7 and 8 the intensity of the synthetic echoes will be doubled inasmuch as wave power will be diverted from and restored to the line 12 through both circuits 13 and 15.

How accurately the several resistors 16 must be positioned along the line 13 in Fig. 5 depends on factors peculiar to the given system, such as the frequency-reflection characteristics of the significant discontinuities and on what echo intensity and echo delay are judged to be objectionable. In the illustrative case for which numerical data are given hereinabove sufficient accuracy will be achieved if taps are available on the neutralizing line 13 at points spaced apart a quarter or a sixth of the wave-length at the highest signal frequency. Under the conditions assumed the wave-length at 2500 kilocycles is 360 feet, and if the velocity of propagation in the lines 12 and 13

is equal, the indicated one-sixth and one-quarter of a wave-length would be 60 feet and 90 feet, respectively.

The practical illustrative embodiment of the invention shown in Fig. 6 can be accommodated to any predetermined spacing of the taps on the neutralizing line. In this figure the neutralizing line 13 is represented as comprising, like the main signal line 22, a pair of coaxial conductors. Branching from the signaling circuit, the neutralizing line 13 is coiled or otherwise disposed so that the predetermined tapping points lie close together, close enough that they can all be connected by electrically short leads to a common terminal board, for example. The several taps can then be connected through resistors 16, as required, to bus-bars 15, which in turn are connected back to the signaling circuit 22. Preferably the line 13 is connected to the circuit 22 at a point between successive stages 20 and 21 of the repeater amplifier, and the bus-bars 15 are likewise preferably connected to such a point so that a reflection-producing discontinuity will not appear at their point of connection to the line. This feature may be employed in any of the embodiments herein disclosed. Where the interstage circuit to which bus-bars are connected is unbalanced or grounded on one side, the phase reversing function described with reference to Fig. 5 may be retained by coupling bus-bars 15 to the balanced circuit terminals of a balanced-to-unbalanced transformer 17, the unbalanced side of which is connected to the interstage circuit. The line 13 may, if desired, be buried or housed in a repeater station, or enclosed within an individual hut. Bus-bars 15 may be shunted by a resistor 18, if desired, to minimize the effects of bridged capacities across the balanced side of the transformer, and particularly to minimize the difference in the effects thereof at different frequencies.

Instances may be encountered in practice where a number of repeater sections of average length are followed by a substantially shorter one. In such instances it may be found advantageous to utilize the modification of the invention that is illustrated in Fig. 7 where a short repeater section bounded by repeaters 10 and 11 is assumed to follow one or more longer repeater sections. The neutralizing line 23-13 is indicated as being connected to the main transmission line at the output terminals of the second repeater 11 and as extending parallel to the main circuit to a point adjacent repeater 10 where the neutralizing line portion 13 is coiled in the manner illustrated in Fig. 6 and terminated in an impedance matching resistor 14. The coiled portion of the line 13 is provided with taps from which neutralizing connections comprising resistors 16 are taken off and connected with the input circuit of repeater 10. The resistors 16 are so adjusted and connected to such taps, as described hereinbefore, as to neutralize echoes appearing in the line. The neutralizing circuit is virtually unilateral in its operation by reason of its connection between a point of high signal level at repeater 11 and a point of low signal level at repeater 10. It is to be observed that in Fig. 7 the delay of a given synthetic echo relative to the signal is measured by the combined lengths of the portion of the neutralizing circuit 23-13 through which it is transmitted and the length of the repeater section between repeaters 10 and 11. By reason of this fact a given delay is achieved in Fig. 7 with a neutralizing line that is little more than half the

length that would be required in accordance with Fig. 6. If there are present in the signaling line echoes having delays too short to be matched with the Fig. 7 arrangement an auxiliary neutralizing line in accordance with Fig. 6 may be connected at repeater 10 or 11, for example, or a shorter backwardly extending neutralizing line in accordance with Fig. 7 may be added at any convenient point to compensate for these echoes of relatively short delay. It should be understood that the principles illustrated in Fig. 7 are not limited in their application to the typical case assumed in which a relatively short repeater section is included in the system.

It was intimated hereinbefore that in a given transmission system the echoes might be found to be divisible into a plurality of sets, the echoes in each set evidencing in common the same frequency distortion relative to the signals. How this condition may arise can be seen readily on reference to Figs. 3 and 4. If the impedance discontinuity at point 8 is of the same degree and character at all frequencies in the signaling range, the echoes due to its presence will tend to be free of frequency distortion. If this principal impedance discontinuity, however, is such that there is a greater mismatch at some frequencies, as for example the lower frequencies in the television range, than at other frequencies, then the different frequency components of the echoes will not be of the same relative intensity as the corresponding components in the signal, and frequency distortion may be said to be present. The other principal discontinuity, that at point 5, may have a different reflection-frequency characteristic corresponding, for example, to a marked discontinuity at the upper television frequencies. To modify correspondingly the several sets of synthetic echoes so that their frequency composition will match that of the echoes to be neutralized, they may be segregated in the neutralizing circuit and respectively corresponding frequency distortion impressed on them.

Fig. 8 will serve to illustrate one arrangement for introducing frequency distortion in a plurality of sets of synthetic echoes. Although it is specifically adapted for only two such sets of echoes, it will be evident that the principles involved can be extended to accommodate any desired number of sets of echoes. In Fig. 8 a neutralizing line 13 is connected to the signal line in the manner of Fig. 5 and two sets of bus-bars 15a and 15b are associated therewith instead of the single set indicated in the preceding figures. As in Fig. 5, the bus-bars are idealized in that they are treated as being electrically short. Connecting each pair of bus-bars with the neutralizing line 13 is an individual set of resistors 16a, 16b, which are proportioned and positioned to neutralize a corresponding set of echoes in the line. The two sets of synthetic echoes delivered to the two sets of bus-bars are separately and differently treated in the respectively corresponding equalizers 25 and 26 before they are introduced into the signaling line. Each equalizer is designed to impress on the set of synthetic echoes applied to it the same modification, as of frequency distortion, that appears in the set of echoes they are intended to neutralize. To avoid interaction between the two equalizers and their associated circuits they may be connected in conjugate relation to each other by a hybrid coil 27 which connects them both through a circuit 28

in energy transfer relation with the signaling line.

Although a uniform electric transmission line, and especially one having the same propagation characteristics as the signaling line, is peculiarly adapted in several respects for the neutralization functions of the present invention, other electrically long wave transducers may advantageously be employed in some cases where the same nicety of adjustment and precision of neutralization are not required or justified. In Fig. 9 the synthetic echo-producing transducer shown takes the illustrative form of an acoustic wave guide or speaking tube 113. At one end of the tube is an acoustic wave generator 30 which is excited by signal power diverted from the signaling line. At its other end the tube 113 is terminated in characteristic impedance by means of acoustic wave power absorbing material 114. Acoustic wave receivers 31 spaced along the tube 113 constitute taps through which wave power may be diverted as required, through respective resistors 116, to a pair of bus-bars 115. It will be clear that a series of sound wave generators used in the location of receivers 31 and a receiver used in the location of sound wave generator 30 would constitute an alternative embodiment.

The synthetic echoes introduced into the signaling line by the bus-bars 115 are adjusted in amplitude by control of resistors 116, and in phase and delay as described hereinbefore, to neutralize echoes appearing in the transmission line. The receivers 31 may be made continuously adjustable longitudinally of the tube 113 to facilitate accurate control of the delay of the synthetic echoes. For signaling waves of speech frequency the acoustic wave generator 30 and the receivers 31 may comprise conventional telephone apparatus, but for higher frequencies and wider transmission bands other devices such as piezoelectric crystals are to be preferred.

It is conceivable that satisfactory adjustment of the echo neutralizing line in any of the foregoing embodiments might be effected by concurrent inspection, aural or visual, of the signal, and that in the case of a television system one could employ a fixed signal pattern especially designed to disclose the presence and other information relating to unneutralized echoes arising in the system. Preferably, however, adjustment of the neutralizing line is effected with the aid of a continuous representation of the echo-producing characteristics of the line. A preferred arrangement is illustrated in Fig. 10.

In Fig. 10 it may be supposed that the echo-producing characteristics of the portion of signaling line 22 that is represented are to be ascertained. At the sending end of the line is a low frequency oscillator 40 and a pulse generator 42 excited thereby and adapted to deliver to the line 22 periodic short current pulses. As each "signal" pulse and its attendant train of pulse echoes arrive at the echo neutralizing point they are diverted from the signaling line and at least the pulse echoes made to appear on the screen of a cathode ray tube 43. The sweep circuit 44 associated with the cathode ray tube is synchronized with the incoming pulses by means of a circuit 41 which connects it with the source 40. A phase shifter 45 may be associated with the sweep circuit to control the position of the image on the screen. When the system is properly synchronized the image of the echoes remains stationary. To eliminate the signal pulse from the circuits of the cathode ray tube a sec-

ond pulse generator 46 similar to pulse generator 42 and excited from synchronizing line 41 may be provided and connected to neutralize the original signal pulses. Neutralization may be effected by means of a hybrid coil 48 with the aid of a phase shifter 47 in the exciting circuit of pulse generator 46. With these features present only the pulse echoes are applied to the deflecting plates of the cathode ray tube and only the pulse echoes appear in the image.

If the pulses generated in device 42 are unidirectional, the image appearing on the screen of the cathode ray tube 43 may take the form suggested by the solid line pattern in Fig. 11. If the pulses are of successively opposite polarity the image will be duplicated in reverse as suggested by the dotted line in Fig. 11. It will be evident that in either case the image indicates the number of echoes, their relative amplitude and relative delay. On connecting to one of the taps of the neutralizing line 13 associated with repeater 11, a synthetic echo will ordinarily appear in the image. By changing the position of the tap the synthetic echo image may be caused to move across the cathode ray tube screen until it coincides in time delay with one of the original echoes. Further adjustment is then made of its amplitude and phase until both substantially disappear. The same procedure is repeated for each significant echo present.

With regard to the wave source 40 in Fig. 10 considerable latitude is permissible as to its operating frequency. What frequency will be found the best will depend on the character of the pulses generated by device 42. The pulses may be, for example, of great intensity but of short duration, even small compared with the semiperiod of the highest normal signaling frequency. This type of pulse is well adapted for exploring the characteristics of the system in the upper frequency ranges. A square top wave of greater duration, on the other hand, is better adapted for the lower portions of the signaling range. If the noise level on the transmission line is high, improved results may be obtained by rounding off the pulses applied to the line. A band-pass filter 49 in the output lead from hybrid coil 48 may be designed to introduce a supplementary rounding off of the signal pulses and at the same time to exclude frequencies lying outside the range for which it is desired to provide echo neutralization.

Although the present invention has been described largely in terms of various illustrative embodiments, it will be apparent to those skilled in the art that the invention and its various features are susceptible of embodiment in a wide variety of forms within the spirit and scope of the appended claims.

What is claimed is:

1. In combination, a signal transmission line, an auxiliary uniform transmission line connected at two geographically separated points thereof in signal transducing relation with said signal transmission line, the total electrical length of the loop formed by said auxiliary line and a portion of the said signal transmission line embraced by said two points being substantially equal to the distance delay of a signal echo arising in said line.
2. In combination with a long distance signal transmission line subject to echo effects, an auxiliary transmission line the electrical length of which is comparable with the delay of echoes in said line, means for exciting said auxiliary line with signals transmitted through said signal transmission line, a plurality of spaced taps along

said auxiliary line for deriving synthetic echoes from said auxiliary line, and means introducing the echoes so derived into said transmission line for the neutralization of echoes arising therein, said auxiliary line being coiled or otherwise so disposed that said taps are physically close together.

3. A combination in accordance with claim 2 in which the propagation constant of said auxiliary line is substantially identical with the propagation constant of said signal transmission line.

4. In a signaling system, a long distance transmission line comprising a plurality of successive repeater sections, each of said sections having therein a plurality of spaced impedance discontinuities that give rise to signal echoes, means at one point along said line for introducing into said line a plurality of synthetic echoes to neutralize the said signal echoes, the pairs of discontinuities in each repeater section that give rise to substantial echoes being equally spaced in all of said sections, the equality of spacing being of such precision that respectively corresponding echoes arising in said several sections effectively coincide for echo neutralizing purposes.

5. The method of mitigating echo effects in a signal transmission system which comprises maintaining the echoes arising in successive sections of said system in superposed relation and introducing into said system synthetic echoes severally phased to neutralize a respectively corresponding set of said superposed echoes arising therein.

6. The method of mitigating ghost images or like distortion effects in a television signal transmission system which comprises diverting television signal waves from said system, propagating said diverted waves through a transmission medium having transmission characteristics substantially identical to those of said transmission system for different electrical distances each comparable with the delay of a ghost image in said system, and introducing the said waves after propagation as aforesaid into said system at such point that the respective delays of said waves so introduced are at said point substantially equal to the delays of respectively corresponding ghost images.

7. In combination, a signal transmission line having a plurality of signal repeaters geographically spaced apart therein, and an auxiliary signal transmission line connecting a point of high signal level at one repeater with a point of comparatively low signal level at an interior repeater, said line being so connected as to divert signal waves from said line at said one repeater and to introduce the diverted signal waves into said line at said anterior repeater, the combined electrical lengths of said auxiliary line and the portion of the signaling line embraced thereby being substantially equal to the delay of a signal echo appearing in said transmission line.

8. In combination, a signal transmission path comprising a plurality of signal repeaters geographically spaced apart therein, said repeaters defining a plurality of successive repeater sections of approximately equal electrical lengths followed by a substantially shorter repeater section, and means for introducing synthetic echoes into said signal transmission path comprising an auxiliary

signal transmission link embracing said shorter repeater section and feeding signal waves back to the input end of said shorter section.

9. A combination in accordance with claim 8 in which said auxiliary link comprises a transmission line that is coiled at said input end of said shorter section, and electrically short signal transducing connections from a plurality of points along said coiled line to said transmission path.

10. In combination with a signaling system, an electrically long signal wave transducer excited by signals traversing said system, means for deriving separate sets of differently delayed synthetic echoes from said transducer, means for modifying the frequency composition of at least one of said separate sets, and means introducing said separate sets after modification into said signaling system.

11. A long distance signal transmission path comprising a plurality of signal repeaters geographically spaced apart therein, an electrically long wave guide excited at one end by signals from said transmission path, an impedance matching termination for said guide at the other end thereof, a plurality of sets of taps for diverting variously delayed synthetic echoes from said guide, an individual equalizer for each of said sets of taps, and means for introducing the corresponding sets of synthetic echoes into said transmission path through said individual equalizers, said synthetic echoes having such delay as to coincide with echoes arising in said transmission path, and said equalizers having such respective transmission characteristics that each of said sets of synthetic echoes is modified with respect to said signal in substantially the same manner as is a respectively corresponding set of said echoes arising in said transmission path.

12. In a long transmission system subject to echo effects, the method which comprises transmitting periodic discrete pulses through said system, receiving said pulses and the correspondingly periodic sets of echoes produced by said pulses, neutralizing the said received pulses and translating said sets of echoes into a visual pattern, whereby the echo-producing characteristics of said system may be observed in said pattern, introducing synthetic pulse echoes into said system at a point such that said synthetic echoes are concurrently received and translated as aforesaid, and adjusting the delay of said synthetic echoes as introduced into said system so that said pattern assumes a predetermined character indicative of substantial neutralization of said echoes.

13. A long distance signal transmission system subject to echo effects, means for introducing a synthetic neutralizing echo into said system comprising an auxiliary transmission path interconnecting geographically separated points in said system for the transmission of signals therebetween, the total length of the loop formed by said auxiliary path and the portion of said system between said geographically separated points being substantially equal to the electrical distance delay of an echo in said system, and means for adjusting the amplitude of said synthetic echo to substantial equality with that of the echo to be neutralized.
